DESIGN FOR A TEXTILE FABRIC

Arthur White, Uxbridge, Mass., assignor to Uxbridge Worsted Company, Inc., Uxbridge, Mass., a corporation of Massachusetts

Application July 8, 1935, Serial No. 57,567

Term of patent 3½ years

To all whom it may concern:

Be it known that I, Arthur White, a citizen of the United States, residing at Uxbridge, in the county of Worcester, State of Massachusetts, have invented a new, original, and ornamental Design for Textile Fabrics, of which the following is a specification, reference being had to the accompanying drawing, forming part thereof.

In the accompanying drawing:—

Figure 1 is a face view of a textile fabric, showing my new design; and

Figure 2 is a transverse section through the fabric, taken on the line 2—2 in Figure 1.

As shown in the accompanying drawing, the design unit is outlined by the dot-and-dash lines, and the design unit is repeated over the surface of the fabric in both directions on each diagonal of the fabric at intervals equal to one or the other diameters of the design unit, and the fabric is woven and in one color.

I claim:

The ornamental design for a textile fabric, as shown and described.

ARTHUR WHITE.
